UNITED STATES PATENT OFFICE.

EDWIN C. KAYSER, OF CINCINNATI, OHIO, ASSIGNOR, BY MESNE ASSIGNMENTS, TO THE HYDROGENATION COMPANY, OF CINCINNATI, OHIO, A CORPORATION OF OHIO.

APPARATUS FOR THE REDUCTION OF METALLIC OXIDS WITH HYDROGEN.

1,134,745.

Specification of Letters Patent.

Patented Apr. 6, 1915.

Application filed July 18, 1910. Serial No. 572,311.

To all whom it may concern:

Be it known that I, EDWIN C. KAYSER, a subject of the King of Great Britain, and a resident of the city of Cincinnati, in the county of Hamilton and State of Ohio, United States of America, have invented certain new and useful Improvements in Apparatus for the Reduction of Metallic Oxids with Hydrogen, of which the following is a full, clear, and exact description, reference being had to the accompanying drawings, forming a part of this specification.

The object of my invention is to provide an effective apparatus for the general treatment of dry substances with gases and the apparatus is more particularly designed for the chemical reduction of metallic oxids with hydrogen when a prolonged intimate contact with a current of the gas is required especially at an elevated temperature.

The apparatus consists of that certain novel construction and arrangement of parts to be hereinafter particularly pointed out and claimed, whereby the material to be treated may be heated to the desired temperature rapidly and uniformly and the gas introduced and withdrawn from the apparatus while the charge is continuously disseminated through the moving gaseous atmosphere.

In the drawings, Figure 1 is a side elevation of my improved apparatus including subsidiary vessels for the separation of entrained material and steam or other admixture from the gas with which the treatment is accomplished. Fig. 2 is an end elevation of the main vessel for treating the material. Fig. 3 is a central vertical section of the same. Fig. 4 is a similar section on an enlarged scale.

1 is a seamless cylinder, preferably of welded steel provided with closed ends 2, 3, preferably of cast iron, suitably bolted or riveted to the cylinder, preferably by bolts or rivets 4, 4, secured through the periphery of the heads and the flanges 5, 6, on the ends of the cylinder. The heads are provided with hollow trunnions 7, 8, which are mounted in pillow blocks 9, 10, in the upper end of substantial standards 11, 12, the pillow blocks holding the boxes forming the bearings for the trunnions 7, 8, so that the vessel is thus suspended to rotate freely in a horizontal position. 13 is a

spur gear mounted on the trunnion 8. Through this spur gear the cylindrical vessel is rotated at the desired rate of speed by driving mechanism not shown. Mounted inside of the cylindrical vessel in fixed position are a series of vanes 14, extending radially from the outer surface of the cylinder toward the center and running lengthwise of the cylinder. As the cylinder is to be subjected to heat, it is important that the cylinder should be seamless and intact and not pierced with rivet or bolt openings. The vanes are therefore secured in position as follows: A cylindrical framework of the internal diameter of the cylinder is formed of a pair of annular angle bars 15, 16, for the ends and a central band or hoop 17, and to these end angle bars and the central hoop are riveted lengthwise a series of angle bars 18, and then to each of these angle bars a metal plate or vane 14 is bolted or riveted so that the plates 14 will extend inwardly toward the center, and the inner ends of these plates are bent slightly lengthwise at 19 in the direction of the proposed rotation of the cylinder. Before one of the heads of the cylinder is secured in place, this framework with the vanes is passed into the cylinder, the head bolted in place and the framework with the vanes secured rigidly to the heads by the bolts 20. In this way, the ends are rigidly secured within the cylinder. Each trunnion of the head is hollow and threaded to receive pipes which open through the cylindrical heads in one direction and extend through the trunnions and terminate and revolve within stationary stuffing boxes 21, 22. These stuffing boxes are threaded to receive gas pipes, 23, which serves as a supply pipe, and 24, which serves as the escape pipe. The supply pipe is provided with the reducing coupling 25, to which is secured the pipe 26 for the supply of the gas from any proper source.

For the purpose of heating the cylinder, a carriage 27 is provided, mounted on wheels 28, running on the track 29, and this carriage is provided with a number of tubular gas burners connected together by T-couplings 30 and controlled by valves 31.

32 is the supply pipe for the gas burners, which is coupled to the burners by coupling 33, so that the gas supply pipe can be easily disconnected to allow the carriage to be with-

100

110

drawn from under the cylinder when desired. In order to properly retain the heat, the cylindrical vessel is provided with a metallic cylindrical hood 34, which extends 5 from the front to the rear of the end standards, completely encircling the cylinder except at the bottom. At the rear and across the ends, the standards are also inclosed with plates 35, 36. The hood 34 is provided 10 with the stack 37, and the lower portion of the hood is formed of removable sections 38, 39, so that when desired the hood can be readily removed from around the cylinder.

For the purpose of cooling down the cylinder, when desired, a spray pipe 40 is provided inserted through the hood at the top and running lengthwise of the cylinder, and at the bottom a perforated steam pipe 41 is located. In order to cool off the apparatus, 15 the burner carriage is withdrawn, steam is first turned on through the pipe 41, and after the temperature of the cylinder has been sufficiently reduced, the spray pipe 40 is turned on. The gas which enters through 20 the supply pipe 23 and escapes through the pipe 24 is turned into the rectangular closed tank or box 42, where any entrained material is deposited and thence the gas is delivered through pipe 43 to the vertical vessel 25 44, where it may be sprayed by a descending spray of water supplied through the pipe 45. The vessel 44 is provided with a water seal 46 and the purified gas escapes through pipe 47, to the supply tank. In 30 order to supply and remove the charge from the cylinder, one of the heads is provided with a manhole 48, and one of the vanes 14 is omitted opposite the manhole. A section of the end angle bar 16 is also removed to 35 40 allow for conveniently scraping out the vessel.

For use, the apparatus is charged with the material to be treated by rotating the receptacle to bring the manhole at the top 45 and then filling in the charge through the open manhole. The manhole is then closed and the heat turned on through the burners, the temperature of the material elevated to the proper point, while the cylindrical vessel 50 is being constantly rotated. The gas is introduced through the center of the apparatus from the supply end and taken out at the delivery end while the heat is maintained, the vanes constantly carrying the 55 material upwardly and dropping it down across the open center and across the gas current. When the treatment is complete, the gas burner carriage is uncoupled and withdrawn from under the apparatus; steam 60 pipe 41 with its spray of steam is turned on to preliminarily reduce the temperature and then the spray pipe 40 is employed to thoroughly cool the apparatus and the charge. The charge is removed by bringing 65 the manhole to the bottom, scraping out the

lower section, then rotating the vessel one turn and repeating the operation until the desired amount is withdrawn.

Having thus described my invention, what I claim as new, and desire to secure by Letters Patent, is:—

1. In an apparatus of the character described, the combination with supporting standards, of a closed seamless cylinder mounted to rotate horizontally therein, gas 75 inlet and discharge pipes to supply a circulation of gas through the cylinder with the principal line of flow along the axis thereof, and numerous vanes secured in fixed position lengthwise the cylinder and 80 projecting inwardly to a point relatively near the axial line of the cylinder, to form compartments with reentering sides, and mouths at the principal point of flow of gas, for the purpose described.

2. In an apparatus of the character specified, the combination with supporting standards, of a closed seamless cylinder, provided with hollow trunnions mounted to rotate horizontally in the standards, gas inlet and discharge pipes connected with the hollow trunnions to supply a circulation of gas through the cylinder along the axial line thereof, and numerous vanes secured in fixed position 90 lengthwise within the cylinder and projecting inwardly in radial planes to a point relatively near the axial line thereof to form compartments with reentering sides and mouths at the principal point of flow of gas, for the purpose described.

3. In an apparatus of the character specified, the combination with supporting standards, of a closed seamless cylinder mounted to rotate horizontally therein, gas inlet and discharge pipes to supply a circulation of 105 gas through the cylinder, and numerous vanes secured in fixed position lengthwise within the cylinder and extending inwardly in radial planes from the interior surface of the cylinder toward the center to leave a 110 free open space around the axis of the cylinder, and to form compartments with reentering sides and mouths at the principal point of flow of gas, for the purpose described.

4. In an apparatus of the character specified, the combination with supporting standards, of a closed seamless cylinder mounted to rotate horizontally therein, gas inlet and discharge pipes to supply a circulation of 120 gas through the cylinder and a tubular framework with vanes secured radially and lengthwise thereto, to form compartments with reentering sides to carry the material to the top of the cylinder, with the framework secured at the ends to the heads of the cylinder to rotate therewith.

5. In an apparatus of the character specified, the combination with supporting standards, of a closed seamless cylinder mounted 130

to rotate horizontally therein, gas inlet and discharge pipes to supply a circulation of gas through the cylinder and vanes secured in fixed position lengthwise and radially 5 within the cylinder to rotate therewith, to form compartments with reëntering sides to carry the material to the top of the cylinder, a portable heater for heating the cylinder lengthwise comprising a wheeled carriage 10 with a series of gas burners thereon and means for connecting and disconnecting the gas supply pipe therefrom.

6. In an apparatus of the character specified, the combination with supporting stands, of a closed seamless cylinder mounted to rotate horizontally therein, gas inlet and discharge pipes to supply a circulation of gas through the cylinder and vanes secured 15

in fixed position lengthwise and radially within the cylinder to rotate therewith, to 20 form compartments with reëntering sides to carry the material to the top of the cylinder, a portable heater for heating the cylinder lengthwise comprising a wheeled carriage with a series of gas burners thereon and 25 means for connecting and disconnecting the gas supply pipe therefrom, with a hood inclosing the cylinder and heater and steam and water spray pipes disposed within said hood for lowering the temperature of the 30 cylinder.
